Albert F. Young INVENTOR
BY Phillips Abbott ATTORNEY

UNITED STATES PATENT OFFICE.

ALBERT F. YOUNG, OF NEW YORK, N. Y.

PENCIL.

Application filed October 1, 1921. Serial No. 504,737.

To all whom it may concern:

Be it known that I, ALBERT F. YOUNG, a citizen of the United States, residing at No. 471 Stratford Road, in the city of New York, county of Kings, and State of New York, have invented certain new and useful Improvements in Pencils, of which the following is a specification, reference being had to the accompanying drawings.

10 It is the purpose of this invention, generally stated, to provide a pencil in which the lead may be quickly and easily supplied at the writing end of the pencil, thus avoiding all necessity for sharpening the same; in 15 which the length of the pencil will always remain the same; in which leads of differing shape and color may be interchangeably used—and which has an attractive appearance, and is convenient in operation.

20 In the drawings—Figure 1, illustrates a longitudinal sectional view of a pencil embodying one form of the invention.

Figure 2, illustrates an elevation of the forward end of the pencil, the tip being removed.

25 Figure 3, illustrates an elevation of the threaded lead holder and lead.

Figure 4, illustrates a cross sectional view of that which is shown in Figure 3.

30 Figure 5, illustrates a cross sectional view on the line 5, 5, of Figure 1.

Figure 6, illustrates an elevation looking at the forward end of the pencil.

35 Figures 7 and 8, illustrate cross sectional views of leads of differing shape.

Figure 9, illustrates a longitudinal sectional view of the tip of the pencil.

40 In the drawings 1, illustrates the body of the pencil which is tubular in form and is threaded interiorly throughout its length as shown at 2. At the rear end the threads are cut away for a space, leaving an enlarged recess or chamber 3. 4 is a cap for the rear end of the pencil which may be held in place by threads 5, or in any other preferred manner.

45 At the forward end, the diameter of the pencil body is reduced, thus producing a forwardly extending part 6 (see Figure 2) in which are made two or

50 more longitudinal grooves 7, 7, which connect with a similar circumferential groove 8 in the part 6; the tip 9 is preferably made as shown in Figure 9, that is to say, tapering in shape and perforated by a hole 10, which is in shape and diameter substantially

55 has a recess 11 in its rear end adapted to fit over the projecting part 6 of the pencil body and it is provided with inwardly extending pins 12, 12 which are adapted to 60 slide through the grooves 7, 7, and enter and move freely through the circumferential groove 8, when the tip and pencil body are rotated relative to each other. 13 is the lead holder. It is preferably a hollow metallic 65 plug-like device, threaded exteriorly as at 14 to match the thread in the body part and is provided with a lead gripping clamp 15. This clamp is rigidly attached to the holder 13 and may be made of such shape 70 as will best aid in holding the lead. In Figure 3 it is shown as a mere flat spring like part having a plate like part at its end arranged at right angles to the spring like part and through which the lead passes. 75

The operation of the parts is as follows: The leads which may be of such shape in cross section and of such density and color as preferred, are engaged with the lead holder either permanently, or preferably by 80 simply pressing them into the hollow interior of the holder, having first passed the end of the lead through the clamp 15, which being of spring metal and offset somewhat will exert a gripping and holding action on 85 the lead when it is straightened into alignment with the threaded bore of the pencil body. The cap 4 being removed the lead is now dropped through the body part until the holder engages with the threads in the 90 interior of the body part. The cap 4 may then be replaced. The tip 9 is now applied upon the forward end of the pencil, care being taken that the lead is not broken during its passage through the tip. If the lead 95 be angular in cross section, then of course the hole through the tip will be of the same form, but if round then in order that the lead may be compelled to rotate on its longitudinal axis when the tip is rotated, I 100 provide the tip with a spring 16, which projects into the lead passage and binds upon the lead, thus assuring its rotation when the tip is itself rotated. It will be noted that since the pins 12—12 on the tip pass through 105 the longitudinal grooves 7 and enter the circumferential groove 8, that the tip may be freely rotated relative to the body part of the pencil without separation therefrom, the connection being in the nature of a 110 bayonet slot joint. It will also be noted that the enlarged space 3 at the rear end of

the body part and a similar enlarged recess or space marked 17 at the forward end are provided so that should the holder 13 at any time be brought by the rotation of the parts relative to each other, into either of these enlarged and threadless spaces, that further rotation will not effect any movement of the lead and thus possible injury or disorganization of any part be avoided.

10 The parts being assembled as above described, it being assumed that the point of the lead projects beyond the tip, the writer uses it as desired and when the projecting lead has worn down, to supply additional lead, the tip is grasped by thumb and finger of one hand and the body of the pencil by the other and being rotated relative to each other the threads on the holder engaging those on the body part will cause the projection of additional lead if rotated in one 20 direction or the retraction of the lead for its protection, if in the other direction.

It will be obvious to those who are familiar with such matters that various modifications may be made in the detail of construction and operation, as illustrated and above described by me and yet the essentials of the invention be employed. I therefore do not limit myself to such details.

25 The various parts of the pencil will, of course, be made of such materials as the experience of the art and the desire of the maker may suggest.

I claim:

30 A pencil having a continuously bored and threaded body part and enlarged threadless spaces at each end of the bore, a threaded lead holder, a tip attached to the body part and adapted to be rotated relative to it and means on the tip which adjustably engage 40 the lead and compel the lead and, through it, the lead holder to revolve with the tip.

ALBERT F. YOUNG.
